BOOK OF MATCHES

Walter G. Stahl, Maywood, Ill.

Application February 4, 1957, Serial No. 44,736

Term of patent 14 years

(Cl. D48—29)

I claim:

The ornamental design for a book of matches, as shown.
